(57) **CLAIM**

The ornamental design for a hand-held laser scanner with LED windows, as shown and described.

DESCRIPTION

FIG. 1 is a perspective, front view of the hand-held laser scanner with LED windows showing our new design;

FIG. 2 is a perspective, rear view thereof;

FIG. 3 is a front view thereof;

FIG. 4 is a rear view thereof;

FIG. 5 is a side view thereof;

FIG. 6 is a top view thereof; and,

FIG. 7 is a bottom view thereof.

The broken lines showing in FIGS. 1–7 are for illustrative purposes only and form no part of the claimed design.

1 Claim, 5 Drawing Sheets
